UNITED STATES PATENT OFFICE.

CHARLES P. MAHOOD, OF LYNCHBURG, VIRGINIA, ASSIGNOR OF ONE-HALF TO WILLIAM B. MULLER, OF NORFOLK, VIRGINIA.

EAVES-TROUGH HANGER.

No. 890,429.

Specification of Letters Patent.

Patented June 9, 1908.

Application filed August 16, 1907. Serial No. 388,880.

To all whom it may concern:

Be it known that I, CHARLES P. MAHOOD, a citizen of the United States, residing at Lynchburg, in the county of Campbell and 5 State of Virginia, have invented certain new and useful Improvements in Eaves-Trough Hangers; and I do declare the following to be a full, clear, and exact description of the invention, such as will enable others skilled 10 in the art to which it appertains to make and use the same.

This invention relates to an improved eaves trough hanger and stay.

The object of the invention is to provide 15 a hanger which is also adapted to serve as a stay for the trough to hold it in proper position against outward bulging or inward bending.

Figure 1 of the accompanying drawings 20 represents a perspective view of a portion of a building having an eavestrough attached thereto by means of this improved hanger. Fig. 2 represents a perspective view of the hanger as it is placed on the market. Fig. 3 25 represents a perspective view of a slightly modified form of hanger.

In the embodiment of the invention herein 30 illustrated an eavestrough 1 of ordinary construction is shown secured to a building by means of this improved hanger which passes 35 through spaced apertures as 2 and 3 in the opposite sides of the trough preferably near the upper edges thereof.

This hanger is preferably made of twisted 35 wire and consists of a stem 5 provided at one end with a spur or spurs 6 which are designed to engage the roof of a building to hold the trough temporarily in position while the proper slant is being attained. This stem 5 40 is provided preferably at one end thereof with oppositely extending lateral arms 7 and 8 which have their free ends divided or forked forming tines 9, 10, and 11, 12 which are offset or bent in opposite directions to 45 form shoulders 13, 14 and 15, 16 which abut against the opposite inner faces of the trough and brace it against inward pressure. These forked ends after being passed through the 50 spaced apertures 2 and 3 of the trough are bent upwardly at right angles to the arms 7 and 8 and then bent forward around the edges of the trough and firmly clamp said sides between the offset shoulders and said bent ends 55 thereby bracing and holding said trough securely against outward bulging or inward bending.

This improved hanger serves as a stay for the gutter as well as a support therefor and may be applied equally well to a gutter having either a single or a double bead. The 60 advantage of this hanger over the old style girth gutter hangers is that no water is held against the bottom of the gutter by the hanger and consequently there is no resulting 65 rusting or leakage in the gutter.

The hanger is placed on the market in the form shown in Fig. 2 with the tines or divided ends thereof lying in flat position ready for insertion through the spaced apertures of the 70 trough.

In the use of this device the tines of the lateral arms 7 and 8 are first passed through the apertures 2 and 3 in the trough until the shoulders 13, 14 and 15, 16 abut against the inner faces of the trough. The forked ends 75 are then bent upward against the outer faces of the trough sides and bent or turned over around the edges of said trough. After a sufficient number of hangers have been applied to the trough it is attached to the eaves 80 by first bending the stems 5 at the proper angle to cause the spurs 6 to engage the roof to which the gutter is to be applied, said spurs 6 holding the trough temporarily in 85 position so that the slant thereof may be tested before the trough is secured permanently. After it has been found that the slant is correct the spurs 6 are driven all the way in and additional fastening devices such as nails or staples are applied by passing 90 them through an eye or eyes 4 formed in the stem 5 near the free end thereof. In the form shown in Fig. 3 the spurs are omitted and an eye 6' formed in place thereof through which a staple or other suitable fastening 95 means may be passed for securing the stem to the roof.

I claim as my invention—

1. A hanger comprising a plurality of wires twisted to form a stem and bent to 100 form oppositely extending lateral arms, said wires being spaced and bent twice at right angles near the terminals of said arms to form forked ends with square shoulders for engagement with the inner faces of the 105 trough when applied, and individual tines adapted to pass through the trough and be bent thereagainst.

2. The combination of an eaves trough 110 having spaced apertures in its opposite edges, a hanger provided with oppositely extending lateral arms arranged transversely of said

trough, each arm having a forked end with the tines of the fork bent in opposite directions at an angle to the arm, to form shoulders for engaging the inner faces of the opposite sides of said trough after the tines have been passed through the apertures in said trough, said tines being bent at an angle on the outer face of said trough.

In testimony whereof I have hereunto set my hand in presence of two subscribing witnesses. 10

CHARLES P. MAHOOD.
